United States Patent Office

Des. 205,328
Patented July 19, 1966

205,328

MULTIPLE PURPOSE VEHICLE

Frederick D. Henry, Torrance, and John R. Clifton, Rolling Hills Estates, Calif., assignors to Northrop Corporation, Beverly Hills, Calif., a corporation of California

Filed Sept. 8, 1965, Ser. No. 86,904

Term of patent 14 years

(Cl. D71—1)

Fig. 1

Fig. 2

FIGURE 1 is a top plan view of the multiple purpose vehicle embodying our new design with the wings thereof unfolded.

FIGURES 2 and 3 are side and front elevational views, respectively, of the multiple purpose vehicle of FIGURE 1.

FIGURES 4 and 5 are front and side elevational views, respectively, of the multiple purpose vehicle of FIGURE 1 with the wings thereof folded along the fuselage of the vehicle.

We claim:

The ornamental design for a multiple purpose vehicle, substantially as shown.
